CAR RETARDER FOR RAILROADS

Filed Dec. 9, 1929

FIG. 1.

FIG. 2.

FIG. 3.

INVENTOR
C. W. Prescott,
BY
Neil H. Pleton,
his ATTORNEY

UNITED STATES PATENT OFFICE

CHARLES W. PRESCOTT, OF MILL HILL, ENGLAND, ASSIGNOR TO GENERAL RAILWAY SIGNAL COMPANY, OF ROCHESTER, NEW YORK

CAR RETARDER FOR RAILROADS

Application filed December 9, 1929. Serial No. 412,757.

This invention relates in general to car retarders, and has more particular reference to a car retarder of the track brake type in which means are provided for effectually preventing car wheels from climbing out from between the retarder brake shoes.

The present invention is an improvement in the invention disclosed in the Howe application 244,259 filed January 3, 1928.

In the use of car retarders of the track brake type, it has been found that there is a tendency for the car wheels to climb up out of the retarder, upon the degree of retardation becoming excessive. This is of course, objectionable in that retardation is prevented and derailment of a car or cars and breakage of various parts is likely.

With the above considerations in mind, it is proposed in accordance with this invention to provide a car retarder, of the type in question, with means for preventing car wheels from climbing out from between the retarder shoes.

More specifically, it is proposed to provide a structure including two spaced pivoted levers arranged to control the degree of retardation by varying the distance between their pivot points, with means for automatically moving one of the pivot points relatively to the other upon a car wheel starting to climb out, whereby to decrease the degree of retardation to the maximum permissible and still have the retarder operative to retard the wheels.

Further objects, purposes and characteristic features of the present invention will appear as the description progresses; reference being made to the accompanying drawings, showing, solely by way of illustration, and in no manner in a limiting sense, several embodiments which the invention can assume. In the drawings:—

Fig. 1 is a transverse sectional view, with parts shown in elevation, of one form of the invention.

Fig. 2 is a transverse sectional view, with parts shown in elevation, of a modified form of the invention.

Fig. 3 is a transverse sectional view, with

parts shown in elevation, of another modified form of the invention.

Referring to the drawings, and first to the form of invention shown in Fig. 1, there is here shown a tie 1, constituted preferably by a steel I beam, supported on any suitable bed 2, such as a wooden tie. Carried on ties 1, of which there is a series as would appear from a plan view, such as in the Howe application above identified, are running rails 3, of the special form shown. Each rail 3 comprises a usual head portion, for receiving the tread of a car wheel, and a downwardly projecting web portion 4, which is vertically slidable between fixed side supports 5, each web 4 being operably connected to an angle arm 6, carried on a fixed pivot 7, the web 4 being pivoted as at 8 to the angle arm 6. The other end of each angle arm 6 is pivoted, as at 9, to an arm 10 carried on a pivot pin 11.

Positioned at each side of each rail 3, is a brake shoe 12, carried in any usual or desired manner by a brake beam 13, each brake beam having an aperture 14 therein, for receiving the upper end of a pivoted arm 15, pivoted as at 16 and 11.

Positioned between the lower ends of the arms 15 at each side of each running rail 3, is a compression spring 17, preferably pretensioned, which constantly operates to bias the lower ends of each pair of arms 15 outwardly away from each other. The brake beams 13 are horizontally slidably mounted relatively to the rails 3, in a direction transverse to such rails, whereby the springs 17 operate to urge the brake shoes 12 inwardly toward the track rails, and to resist any tendency to separate the brake shoes 12.

In one of the brake beams 13 of each pair of brake beams associated with each rail 3, is a centering spring 18, arranged to center the brake shoes 12 at an equal distance from each side of the rail 3, it being clear that otherwise these brake shoes might assume an uncentered position without in any manner affecting the tension of the retarding spring 17.

Controlled by any usual or desired means, such, for example, as a motor, as shown in the Howe application, is a rod 19, slideable trans-

versely of the rails 3 and positionable in any one of several positions, and held in such positions by means of crank and lever mechanism 20, 21, etc., as for example, in the Howe application above identified. Fastened to rod 19 are blocks 22, one for each running rail, in which are mounted the pivot pins 16, whereby movement of rod 19 results in bodily moving the pivot pins 16.

10 The other pivot pin 11 for each running rail, is carried by the arm 10 connected to the angle lever 6, and is mounted to be movable thereby, in a horizontal direction toward and away from rail 3, according as rail 3 is depressed and raised in its guides 5.

15 A consideration of the structure just described, makes it clear that the resistance to separating brake shoes 12 increases as the pivot pins 16 and 11 are brought closer together, and that these pivot pins can be brought closer together by moving rod 19 to the left as viewed in Fig. 1, if pivot pin 11 be held against movement. This pivot pin 11, however, as just described, is not held in 25 fixed position, but is controlled by movement of its running rail 3.

20 Assume the parts shown in Fig. 1 to be positioned for the lowest degree of retardation. On moving rod 19 to the left to its first position, for example, and holding it in such position, the force exerted on pivot pin 16, by rod 19, is transmitted through the lower end of the right hand arm 15, then through spring 17, and through the companion arm 15, to 35 bodily move pivot pin 11 to the left, whereby spring 17 is not additionally tensioned by movement of the rod 19 and the degree of retardation is not at all changed with the track rail 3 unoccupied.

40 On occupancy of track rail 3, however, this rail is depressed to bring its head against the guide members 5, and thereby operates through angle lever 6 to draw pivot pin 11 inwardly toward the track rail and hence toward pivot pin 16. As a result, the pivot pins 11 and 16 are brought together, on occupancy of the track rail 3, to the position they would have at once assumed, had pivot pin 11 been fixed instead of movable. With the pivot pins so positioned, and held, by rod 19 and the weight of the car, the degree of retardation exerted by the brake shoes 12 is dependent on the position of the pivot pin 16, or, in other words, is dependent on the position to which rod 19 has been moved and held.

45 If now, for any reason, a car wheel should start to climb out from between the retarder shoes 12, the weight on rail 3 is immediately relieved, with the result that spring 17 moves pivot pin 11 outwardly, away from the track rail, so as to increase the distance between the pivot pins 11 and 16, and so reduce the degree of retardation to the maximum which is permissible and still not cause the wheel to climb out.

In this manner a means is provided which automatically operates to sufficiently reduce the degree of retardation only sufficiently to prevent any climbing out of the car wheels, and thus prevent derailment, etc.

70 The necessary amount of movement of the rail 3 for effecting this operation is very slight, and has been exaggerated in the drawing for the purpose of illustration. The movements of pivot pin 11 and track rail 3 75 are limited, as by a stop pin 23 or the like.

The arrangement of parts for each track rail 3 is identical, and likewise for a double track road the arrangement of Fig. 1 would 80 simply be duplicated.

The positions of the stop pins 23, can of course be varied in accordance with requirements, as can also be varied the lever ratios of the various levers 4, 6, 10, 15, etc. Likewise the tensions of the springs 17 and 18 can be 85 varied as required in practice under various conditions.

90 The retarding spring 17 is preferably of such a strength, and is so tensioned, that with the pivot pin 16 moved inwardly toward its track rail 3 to the greatest possible extent, corresponding to the maximum degree of retardation, the lightest car to be retarded is heavy enough to fully depress rail 3 until its head contacts with its guide members 5. 95 Under these conditions, the degree of retardation exerted on any car, is independent of the weight of the car, and is dependent upon the position to which rod 19 has been moved and held.

100 On consideration, it is clear that the retarder spring 17 can be made stronger, so that it is possible to move the pivot point 16 inwardly toward the running rail a sufficient distance to prevent a car of a given weight, one of the lighter cars to be handled, for example, from fully depressing rail 3. Under such conditions, the maximum retardation possible without climbing out, is exerted on such a car, this retardation being determined by the weight of the car itself, and being exerted regardless of whether or not the pivot pin 16 be moved further inwardly toward the track rail.

110 It is thus seen that by adjusting the tension and strength of the retarding springs 17, it is possible to exert maximum retardation on cars below a certain weight, either regardless of the position of the pivot pin 16, or regardless of its position inwardly beyond a predetermined point, and at the same time having the degree of retardation exerted on heavier cars, dependent at all times on the position of the pivot pin 16, and independent of the weight of the car.

115 The running rails 3 are flexible enough to permit sufficient raising, upon a car wheel starting to climb out of the retarder, to permit the required reduction of retardation for preventing the wheel from climbing out. As 120

this necessary movement is very small, the ordinary steel rail has sufficient flexibility to permit this operation, even though car wheels directly back or in front of the wheel tending to climb out, are not tending to climb out.

It is of course possible, in cases where a greater movement of the track rail than is permitted by the flexibility of the continuous steel rail, is necessary or desirable, to provide a jointed or articulated rail so as to permit flexibility in a vertical plane sufficient to reduce the degree of retardation enough to prevent climbing out of the car wheels. It is possible, with particular lever ratios of the various levers involved, that the flexibility of a continuous steel rail might not be sufficient to sufficiently reduce the degree of retardation under all conditions. In such cases the flexible rail referred to would be used in place of a continuous rail.

Referring now to Fig. 2, there is here shown a modified form of the invention, in which the running rail 3¹ is not movable, but the angle lever 6 is actuated by an auxiliary rail 24, positioned along the side of the running rail 3¹, in position to receive the weight, or part of the weight on a car wheel, through the flange of such wheel.

In the form of Fig. 2, the operation is substantially the same as described above in connection with Fig. 1. Upon a car occupying the running rail 3¹, the wheel flanges bear on rail 24 to thereby depress this rail and bring pivot pin 11 inwardly toward rail 3¹ to thereby maintain the predetermined degree of retardation desired, unless the car wheel tends to climb out, at which time rail 24 raises to thereby more widely separate pivot pins 11 and 16, to sufficiently reduce the degree of retardation to prevent any climbing out.

Referring now to Fig. 3, there is here shown another embodiment of applicant's invention, in which the running rail 3¹ is carried on heavy coil springs 25 received in sockets in ties 26, there being a spider frame 27 connecting rail 3¹ to one end of angle lever 6. In this form of the invention, the track rail 3¹, on a car occupying the retarder, is pressed down into contact with the tie 26 to thereby operate angle lever 6 and associated parts, as described in connection with the first two forms of the invention.

In the form of Figure 3, the joints 8¹ and 9¹ are knife edge bearing joints, as shown, instead of pin joints as in Figs. 1 and 2.

In the forms shown in Figs. 2 and 3, usual running rails 3¹ can be employed, the auxiliary rail 24 of Fig. 2, being inherently flexible enough for proper operation, or being articulated in a vertical plane to make it more flexible, if desired, in the manner described in connection with rails 3 of Fig. 1, and rail 3¹ of Fig. 3, they being made more flexible by forming them of a plurality of

short articulated sections, if desired, all as described in connection with rail 3 of Fig. 1.

The proportions, sizes, and shapes of the various members involved in the above described structure, can be widely varied in accordance with the attendant circumstances, to fit them in practice for varying conditions of operation, without departing from the present invention.

The above rather specific description of several devices embodying this invention, is given solely by way of illustration, and is not intended, in any manner whatsoever, in a limiting sense. Obviously, this invention can assume many different physical forms, and is susceptible of various modifications, and all such forms and modifications are intended to be included in this invention, as come within the scope of the appended claims.

Having described my invention, I now claim:—

1. In a car retarder, in combination, a running rail, a retarder shoe adjacent each side of the rail and movable away from the rail against biasing means urging the shoes inwardly toward the rail, manually controllable adjusting means for varying the strength of the biasing effort, and means for reducing the strength of the biasing effort in proportion as the rail is relieved of a load.

2. In a car retarder, in combination, a running rail, a retarder shoe adjacent each side of the rail and movable away from the rail against biasing means urging the shoes inwardly toward the rail, manually controllable adjusting means for varying the strength of the biasing effort, when a load is applied to the rail, and means for reducing the strength of the biasing effort in proportion as the rail is relieved of its load.

3. In a car retarder, in combination, a running rail, a retarder shoe adjacent each side of the rail and movable away from the rail against biasing means urging the shoes inwardly toward the rail, manually controllable adjusting means for varying the strength of the biasing effort, and means operatively interconnecting the rail and the shoes for reducing the strength of the biasing effort, in proportion as the rail is relieved of a load.

4. In a car retarder, in combination, a retarder shoe adjacent each side of a running rail, a pivoted arm carrying each shoe, biasing means constantly urging the arms to rock on their pivots to bias the shoes toward the rail, manually controllable adjusting means for moving one of the arm pivots for varying the distance between the two arm pivots to thereby vary the strength of the bias on the shoes, and means causing the other arm pivot to be bodily moved according as a load is applied to, and removed from, the rail.

5. In a car retarder, in combination, a retarder shoe adjacent each side of a running

5 rail, a pivoted arm carrying each shoe, biasing means constantly urging the arms to rock on their pivots to bias the shoes toward the rail, manually controllable adjusting means 10 for moving one of the arm pivots for varying the distance between the two arm pivots to thereby vary the strength of the bias on the shoes, and means causing the other arm pivot to be bodily moved toward, or away 15 from, the manually controllable arm pivot, according as a load is applied to, or removed from, the rail.

6. In a car retarder, in combination, a running rail, a pivot at each side of the rail and 15 movable toward and away from, the rail, an arm carried by each pivot, a brake shoe on each arm and adjacent the rail, biasing means 20 acting on the arm to bias the shoes toward the rail with a force varying with the distance between the pivots, manually controlled means for moving one of said pivots, and automatic means for moving the other pivot in accordance with the load on the rail.

7. In a car retarder, in combination, a running rail mounted to move vertically between 25 fixed guides, a pivot at each side of the rail and movable toward and away from, the rail, an arm carried by each pivot, a brake shoe on each arm and adjacent the rail, biasing 30 means acting on the arm to bias the shoes toward the rail with a force varying with the distance between the pivots, manually controlled means for moving one of said pivots, and automatic means for moving the other pivot in accordance with the load on the rail.

8. In a car retarder, in combination, a running rail mounted in fixed position, and a vertically movable auxiliary rail adjacent the running rail to receive the flange of a 40 wheel on the running rail, a pivot at each side of the rail and movable toward and away from, the rail, an arm carried by each pivot, a brake shoe on each arm and adjacent the rail, biasing means acting on the arms to 45 bias the shoes toward the rail with a force varying with the distance between the pivots, manually controlled means for moving one of said pivots, and automatic means for moving the other pivot in accordance with 50 the load on the rail.

9. In a car retarder, in combination, a running rail, a pivot at each side of the rail, and movable toward and away from, the rail, an arm carried by each pivot, a brake shoe 55 on each arm and adjacent the rail, biasing means acting on the arms to bias the shoes toward the rail with a force varying with the distance between the pivots, manually controllable means for moving one of the 60 pivots, a lever connection between the other pivot and the rail, and means mounting the rail for vertical movement, whereby vertical movement of the rail moves said other pivot to thereby automatically vary the biasing 65 force.

10. In a car retarder, in combination, a running rail, a retarder shoe adjacent each side of the rail and movable away from the rail against biasing means urging the shoes inwardly toward the rail, and means operatively interconnecting the rail and the shoes for reducing the strength of the biasing effort, in proportion as the rail is relieved of a load.

11. In a car retarder, in combination, a 75 retarder shoe adjacent each side of a running rail, a pivoted arm carrying each shoe, biasing means constantly urging the arms to rock on their pivots to bias the shoes toward the rail, and operative connecting means between one of the arm pivots and a load on the rail, including means slidably supporting the rail for vertical movement, and a connection between the rail and the arm pivot, whereby to cause the one arm pivot to be 80 bodily moved according as a load is applied to, and removed from, the rail.

12. In a car retarder, in combination, a retarder shoe adjacent each side of a running rail, a pivoted arm carrying each shoe, biasing means constantly urging the arms to rock on their pivots to bias the shoes toward the rail, and operative connecting means between one of the arm pivots and a load on the rail, including resilient means slidably supporting the rail for vertical movement, and a connection between the rail and the arm pivot, whereby to cause the one arm pivot to be 85 bodily moved according as a load is applied to, and removed from, the rail.

13. In a car retarder, in combination, a retarder shoe adjacent each side of a running rail, a pivoted arm carrying each shoe, biasing means constantly urging the arms to rock on their pivots to bias the shoes toward the rail, and operative connecting means between one of the arm pivots and a load on the rail, including means slidably supporting the rail for vertical movement, and a pivot pinned connection between the rail and the arm pivot, whereby to cause the one arm pivot to be 95 bodily moved according as a load is applied to, and removed from, the rail.

14. In a car retarder, in combination, a retarder shoe adjacent each side of a running rail, a pivoted arm carrying each shoe, biasing means constantly urging the arms to rock on their pivots to bias the shoes toward the rail, and operative connecting means between one of the arm pivots and a load on the rail, including resilient means slidably supporting the rail for vertical movement, and a connection between the rail and the arm pivot, whereby to cause the one arm pivot to be 100 bodily moved according as a load is applied to, and removed from, the rail, said connecting means including knife edge pivots.

15. In a car retarder, in combination, a re-

tarder shoe adjacent each side of a running rail, a pivoted arm carrying each shoe, biasing means constantly urging the arms to rock on their pivots to bias the shoes toward the rail, a member slidably mounted adjacent the rail to receive at least part of the load of a wheel on the rail, and connecting means between said member and one of the arm pivots, whereby to cause the one arm pivot to move as a wheel passes over the rail.

In testimony whereof I affix my signature.
CHARLES W. PRESCOTT.
